BUILDER'S APPLIANCE.

1,113,167.

Specification of Letters Patent.

Patented Oct. 6, 1914.

Application filed March 24, 1913. Serial No. 756,290.

To all whom it may concern:

Be it known that I, ESAIAS T. STADIG, a citizen of the United States, residing at Cambridge, in the county of Middlesex, State of Massachusetts, have invented a certain new and useful Improvement in Builders' Appliances, of which the following is a specification, reference being had therein to the accompanying drawings.

10 My invention relates to appliances intended for use by carpenters, builders, or draftsmen, and is designed to assist such workmen in the task of determining more especially the side-cuts for wooden rafters or similar pieces formed of steel or other structural material, as well as in other work relating to the framing of buildings and requiring angular measurements or cuts.

15 The object of my invention is to produce an appliance of the above character which will be capable of application to facilitate the determination of such cuts or measurements by purely graphical methods and to eliminate so far as possible the necessity 20 for mathematical computations or geometrical processes, whether such roof be square, or of other polygonal outline.

25 My invention consists in an appliance which is essentially a square as commonly known in the builders' trade; but having the long arm prolonged beyond the short arm or blade (hereinafter termed the tang) forming an extension arm; on which arms are carried certain scales relating to linear 30 and angular measurements so arranged and so correlate with respect to each other that my appliance may be used as hereinafter set forth to accurately determine graphically, in a given situation, and in case of a 35 roof of any polygonal outline the various angular and linear measurements relating to rafters or other structural pieces as hereinafter set forth.

40 In the drawing the figure shows my invention in one of its preferred embodiments.

45 Referring to the figure,—my appliance is made up of a preferably integral piece of suitable material, as for example brass

or steel, embodying a long arm *a*, a short arm or tang *b*, and an extension arm, or extension *c*; the tang *b* being perpendicular to the arm *a* and the extension *c*, and the extension *c* constituting a prolongation of the arm *a* beyond the tang *b*.

50 Inasmuch as my appliance is designed to be employed in many of its relations, either in place of, or in conjunction with, the square commonly used by carpenters I find it to be desirable for practical reasons to adopt the following dimensions for my appliance in one of its more popular embodiments: The arms *a* and *c* are respectively 21" long and 7" long, assuming the same to extend to their point of interconnection midway of the width of the arm or tang *b*. 55 Both said arms are 1½" wide. The arm or tang *b* is 2" wide and 8½" long. Thus the total length of the base of my appliance from the end of the arm *a* to the end of the arm *c* is 28" and from the end of the tang *b* 60 to the outer edge of the base of my appliance, which outer edge is the edge opposite to that from which the tang *b* projects, is 10". 65

70 The novelty of my appliance resides in the provision of certain scales which are marked upon the arms *a*, *b*, and *c* in the relation as hereinafter described. Upon one face of my appliance is marked a scale *P* of angle divisions converging at a center point *s* located on the edge *c'*, such edge *c'* 75 being in a line and coincident with a continuation of the edge *a'* beyond the tang *b*, and such center point *s* preferably being at the corner of the said extension *c*; such scale of angle divisions indicate the amount 80 of angular displacement of a line joining each such division with said center point with respect to said edge *c'*. Such angle 85 divisions are arranged to intersect a line on the tang *b*, which lies perpendicular to the edge *c'*, and to the edge *a'* continued, and meeting the same at the point *g*; such perpendicular line preferably being furnished by the edge *b''* of the tang *b*, and the point *g* being preferably at the corner included 90 between the tang *b* and extension *c*. For 95

further convenience the divisions of the angle scale P at 45° , 30° , 36° , $22\frac{1}{2}^\circ$, 18° , and 15° , (the angles corresponding to the quotients obtained from a division of 180° by the number of sides, respectively, in a square, a pentagon, a hexagon, an octagon, a decagon, and a dodecagon,) are respectively extended partway across the face of the tang b as indicated, and in columnar arrangement upon such face of the tang b is marked respectively in correspondence with the scale division so extended figures tabulated as "number of sides in polygons." To avoid a crowding of numerals in the drawing, only the angles above mentioned are illustrated in the figure but the number of the same presented upon my appliance in practice, may be increased to include the corresponding angles for all polygons which are liable to be encountered in the practice of the building trade.

Upon one face of the arm a of my appliance is carried a scale N comprising a series of divisions which intersect a reference line upon the arm a; (which line is preferably the edge a' of such arm a, on the side of the same from which the tang b projects). Each of such divisions is numbered in correspondence with a specified number of inches, or other linear units, of rise for an assumed length of run in a jack rafter. The divisions so numbered are so located with respect to the point g at which the edge b'' of the tang b meets the edge c', which is a continuation of the edge a', that the distance from the point g to any division of the scale N corresponding to a specified rise, is equal to the length of a common rafter having a run equal to the distance between the point g and the point s forming the center of the angle square and the specified rise.

As a result of the correlation of the scales N and P as above described, when it is desired to lay off the side cut upon a jack rafter K which is designed for use in the construction of a roof whose plan lines correspond with the outline of a polygon, it will be found that if my appliance be laid upon the said rafter K so that the rafter edge k is in simultaneous registration with the division of scale N corresponding to the specified rise (for example $18''$ rise per foot in the figure) and with the point at which the edge b'' is intersected by the division of the angle scale P determined by dividing 180° by the number of sides in a polygon corresponding to the outline of the roof (C for example being such point for use in case of a hexagonal roof) the inclination of the said edge a' with respect to the edge k of the rafter K will correctly indicate the angle of the side cut k' for such jack rafter.

Having described my invention, and in what manner the same is to be performed, I declare that what I claim is:

1. A builder's appliance embodying an arm a, an arm c forming an extension of arm a, and a tang b having an edge b'' lying perpendicular to the arm or extension c and meeting the same at a point g, said tang having marked thereon a scale of angle divisions described about a center point s located on said extension and intersecting said edge b'' and said arm a having marked thereon a scale of divisions intersecting its edge a' and numbered to correspond with differing amounts of rafter rise per unit of run, the scale division corresponding to a specified rafter rise being located at a distance on the edge a' from the point g equivalent to the length of a common rafter having a run equal to the distance between the point g and the center s of the angle scale and the specified rafter rise; whereby the inclination of the said edge a' with respect to the edge of a jack rafter positioned in registration with the point of intersection of a selected rafter-rise scale division and said edge a' and with the point of intersection with the said tang edge b'' of the angle scale division corresponding to the angle determined by dividing 180° by the number of sides in a polygon having the plan lines or outline of the roof for which said rafter is intended, will indicate the inclination of the side-cut for jack rafters having the specified rise in a roof of such outline.

2. A builder's appliance embodying an arm a, an arm c forming an extension of arm a, and a tang b, said arm a having marked thereon a scale of rafter rise divisions arranged to intersect a reference line carried on said arm a, said tang b carrying thereon a reference line lying perpendicular with respect to said first mentioned reference line and having marked thereon a scale of angle divisions described about a central point located upon the extension c, positioned upon a continuation of the said first mentioned reference line upon the arm a, which angle divisions intersect said perpendicular reference line on tang b; the scale division corresponding to a specified rafter rise being located on the arm a at a distance from the point at which the reference line on arm a, or its continuation, is intersected by the perpendicular reference line on the tang b, which is equivalent to the length of a common rafter having a run equivalent to the distance between the point of intersection, just mentioned, and the center of the angle scale, and having the specified rise; whereby the inclination of the said arm a with respect to a jack rafter positioned with its edge in registration with the point of intersection of a selected rafter-rise scale division and said reference line on the arm a, and with the point of intersection with the said perpendicular reference line on the tang b of the angle scale division cor-

responding to the angle determined by dividing 180° by the number of sides in a polygon having the plan lines or outline of the roof for which said rafter is intended, 5 will indicate the inclination of the side-cut for jack rafters having the specified rise in a roof of such outline.

In testimony whereof I affix my signature in presence of two witnesses.

ESAIAS T. STADIG.
